UNITED STATES PATENT OFFICE.

HENRY THOMPSON, OF LONDON, ENGLAND.

CONSTRUCTION OF DOMESTIC STOVES AND GRATES.

SPECIFICATION forming part of Letters Patent No. 308,290, dated November 18, 1884.

Application filed May 20, 1884. (No model.) Patented in England February 14, 1883, No. 812, and January 1, 1884, No. 144,

To all whom it may concern:

Be it known that I, HENRY THOMPSON, of London, England, builder, have invented certain new and useful Improvements in the Construction of Domestic Stoves and Grates, of which the following is a specification, reference being had to the accompanying drawings.

My said invention relates to improvements in the construction of domestic stoves and grates, whereby the coal or other fuel is supplied to the fire from a chamber at the back of the grate, the amount of smoke escaping up the chimney is greatly diminished, while at the same time a considerable economy in the consumption of fuel, as compared with stoves and grates of ordinary construction, is effected. The fire in the improved stove or grate is similar in appearance to the fire in an ordinary open stove or grate. The front bars, the bottom, and the sides of the stove or grate are constructed and arranged in the ordinary manner, and the back, which consists of a metal plate, instead of being fixed as in ordinary stoves, is pivoted at the bottom, and is so arranged as to be capable of revolving backward from its normal upright position into a more or less horizontal position. The said back of the stove or grate is prolonged at the bottom below its pivots, such prolongation acting as a weight to counterbalance that portion of the back which is situated above the said pivots, and by so doing tends to maintain the back in an upright position. The said back turns on its pivots within a chamber at the back of the stove, and when in an upright position forms the front side of such chamber, while when in a more or less horizontal position it forms the bottom of the same. The upper part of the said chamber is formed by the prolongation of the back thereof, which is arranged to extend between the chamber and the lower part of the chimney, and in order to allow of the supply of fuel to the chamber the extremity of the said projecting portion is arranged to turn on pivots, so that when such hinged portion is turned back a channel is presented, through which the fresh fuel can be supplied to the chamber, the back of the stove or grate having been brought for that purpose into a more or less horizontal position, as hereinbefore described.

The chamber having been supplied with the desired quantity of fuel, the said hinged projecting portion is returned to its normal position. 55

In order to allow of the proper combustion of the gases and smoke evolved by the fuel contained within the chamber at the back of the stove or grate, the lower face of the hinged upper portion of the back of the chamber is perforated, such perforations serving to conduct the gases and smoke to perforations leading to a channel or channels which passes or 60 passes at the rear of the chamber and opens or open at a point below the fire-bars. (In some cases the whole of the back of the chamber is perforated for effecting the same object.) The gases and smoke will then be drawn into the fire and there consumed. The space between 65 the front of the fire-bars and the hearth is in some cases more or less closed by a plate, which may be provided with apertures for regulating the admission of air.

In some cases a bar is arranged to project 75 below the end of the hinged portion of the upper part of the back of the said chamber, so as to assist in preventing the escape of smoke between the upper surface of the fuel and the extremity of the said hinged portion of the 80 back of the chimney.

I will now proceed to refer to the accompanying drawings, from which the nature of my said invention will be more clearly understood.

Figure 1 is a front elevation of a stove constructed as hereinbefore described, and Fig. 2 is a vertical section through the center of the same.

The same letters of reference indicate like parts in both the figures. 90

A is the front of the stove.

B are the front bars. C is the bottom. The back of the stove is shown at D, and is pivoted at d.

D' is the weighted prolongation of the back. 95 E' is the back of the chamber E, and e is the hinged projecting portion of the same.

In Fig. 2 the back of the stove is shown in a more or less horizontal position, and the hinged projecting portion e of the back of the chamber E is shown open—that is to say, in the requisite position to permit of the said chamber being charged with fuel. The positions of these parts are, however, shown re-

versed in dotted lines—that is to say, the projecting portion *e* is shown closed and the back *D* is shown in an upright position—a position it would assume when all the fuel had been 5 discharged from the chamber *E*.

F is the channel, through which the gases and smoke or a portion thereof pass from the chamber *E* to a point below the fire-bars, and *G* is the before-mentioned plate for closing or 10 partially closing the front of the space between the fire-bars and the hearth. The bar projecting below the hinged upper part of the back of the chamber *E* is shown at *H*.

The fuel having been supplied onto the 15 more or less horizontal back *D* of the stove or grate, as hereinbefore described, is brought forward into the fire in the body of the grate or stove by the rising of the said back as the fuel is consumed in the said stove or grate, 20 such rising being facilitated by the action of the weighted prolongation *D'* or other means.

I lay no claim to anything shown in German Patent No. 3,919, of 1877.

What I claim is—

25 1. The combination and arrangement of the pivoted back *D*, chamber *E*, and the hinged or pivoted projecting portion *e* of the back of

the said chamber, substantially as and for the purposes hereinbefore set forth and described.

2. The combination and arrangement of the 30 pivoted back *D*, chamber *E*, the hinged or pivoted projecting portion *e* of the back of the said chamber, and the bar *H*, substantially as and for the purposes hereinbefore set forth and described.

3. The channel *F*, formed at the back of the fuel-chamber, for conducting the gases and smoke from the upper part of the chamber *E* to a point below the fire-bars, substantially as and for the purposes hereinbefore set forth and 40 described.

4. The channel *F*, formed at the back of the fuel-chamber, for conducting the gases and smoke from the upper part of the chamber *E* to a point below the fire-bars, the space between the front of the latter and the hearth being more or less closed by the plate *G*, substantially as and for the purposes hereinbefore 45 set forth and described.

HENRY THOMPSON.
